UNITED STATES PATENT OFFICE.

LUCIUS J. PHELPS, OF PASSAIC, NEW JERSEY, ASSIGNOR TO DICKSON D. MACMULLEN, OF BROOKLYN, NEW YORK.

LUBRICATOR.

SPECIFICATION forming part of Letters Patent No. 424,350, dated March 25, 1890.

Application filed January 21, 1890. Serial No. 337,620. (No model.)

To all whom it may concern:

Be it known that I, LUCIUS J. PHELPS, of Passaic, county of Passaic, and State of New Jersey, have invented certain new and useful 5 Improvements in Lubricators, of which the following is a specification.

My invention relates, generically, to lubricators, and specifically to that class of lubricators adapted and employed for lubricating 10 the journals of railway-car axles, although it may be applied to other large bearing-surfaces, especially in instances where the waste or loss of oil is liable to occur from the jolting or from other disturbances of the rotating 15 parts.

The object of my present invention is to provide a more convenient and economical device for lubricating journals; and it consists of a modification and improvement on the 20 construction disclosed and claimed in United States Letters Patent No. 368,774, granted to Dixon D. MacMullen, of Brooklyn, New York, August 23, 1887.

In the construction disclosed in the above- 25 mentioned patent an oil-feeding device consisting of a wick extending downwardly into the oil-chamber and upwardly to the lower surface of the journal, whereby the oil or other lubricating material is automatically and constantly fed thereto, thereby supplying the 30 bearing-surfaces with a sufficient quantity of oil and preventing unnecessary waste of the valuable lubricating material, is shown.

The present improvements have been designed to obviate any possible waste of oil 35 which might occur in the use of the device disclosed in the aforementioned patent.

In the first place, to prevent an overfeeding of the lubricating material, I reduce the area 40 of the surface of contact between the wick and the journal, and to prevent the wick from being forced from its position I support it independently of the oil-reservoir upon spiral and helical springs, so that it will automatically 45 return to its normal and proper position if momentarily displaced.

Referring to the accompanying drawings, which form a part of this specification, Figure I represents a longitudinal section of the 50 journal-box of a car-axle journal with my invention applied; and Fig. II represents a de-

tail view, to a larger scale, of the wicking contrivance.

In the drawings, A represents the journal-box of a car-axle lubricator; B, the usual 55 hinged cap thereof.

C represents the journal of the axle G.

E represents the pan or reservoir for holding the oil or lubricating material F. This pan or reservoir is provided with overhanging lips or rims D, so that the oil in dripping from the journal will feed back into the pan or reservoir. An opening H is provided for refilling the pan or reservoir without necessitating the removal of it from the car-axle box, 65 the operator having merely to lift the cap B and apply the nozzle of his oil-can to the opening H.

At J, I show a cover for the pan or reservoir. This cover is removable and can be lifted from 70 the pan and removed from the car-axle box and withdrawn through the door B without disturbing the position of the oil-pan. At the back and inside of the pan are tracks K, on which the cover J travels when it is being replaced upon the pan. At L, also, are shown 75 small tracks which guide the cover when it is first inserted. These same tracks provide means for the easy withdrawal of the cover.

At M is a handle or chain, by which the 80 cover may be manipulated by the operator.

Centrally located are two or more wicks N, attached at their upper ends to the spiral and helical springs O, hereinbefore referred to, and which constitute the wick holders or supports, 85 and which are adapted, as shown in Fig. I, to hold the upper ends of the wicks against the lower surface of the journal of the car-axle, thus supplying a constant feed of the lubricating material, into which the lower ends of 90 the said wicks are adapted to extend to said bearing-surfaces. I provide additional retaining devices P, which connect the upper ends of the spring wick-holders to the cover of the pan, and which serve to retain the wick-holders in their proper places—that is to say, 95 centrally as regards the wick-opening Q in the oil-pan covers.

When the lubricator is in use, it assumes the position shown in Fig. I—that is to say, 100 the spring wick-holders containing the wicks are in an upright position and the tops of the

wicks are in constant contact with the journal-bearings. When the pan-cover is removed, the wick-supports assume the position shown in Fig. II.

5 At the upper end of the spring wick holders and supporters are small nuts R, which are provided on their interior surface with screw-threads. When it is desired to raise or lower the wicks, they may be turned in the proper direction for their adjustment. Of course, instead of two wicks, I may use only one, or I may use three or more without departing from the spirit of my invention.

10 As above stated, the oil-pan cover can be easily removed without disturbing the oil-pan itself, and the latter can likewise be withdrawn through the opening in the car-axle box when desired. By this means, the pan and pan-cover being independently removable, many and obvious advantages obtain by reason of the employment of this particular lubricator, which have been heretofore lacking.

15 Having thus described my invention, what I claim as new therein, and desire to secure by Letters Patent, is—

20 1. In a lubricator, the combination of the removable oil-pan adapted to seat in a car-axle journal-box, an independently-removable

cover therefor, and wicks mounted on springs 30 independently of the oil-pan, all arranged substantially as and for the purposes set forth.

2. In a lubricator, the combination of the removable oil-pan adapted to seat in a car-axle journal-box, a cover therefor having openings 35 for the reception of wicks, helical spring wick-supporters, and suitable wicks mounted therein, all arranged substantially as shown and described, and for the purposes set forth.

3. In a lubricator for car-axle journal-boxes, 40 the combination of the oil-containing pan or reservoir, the removable lid having the elastically-supported wicks, as shown, and the tracks K and L, as and for the purposes set forth.

4. In a lubricator for car-axle journal-boxes, the combination of the removable oil-pan adapted to seat within the journal-box, with the independently-removable cover provided with spring wick-supporting devices, whereby 50 either the cover or pan can be removed without displacing or interfering with any part of the journal-box or car-axle journal.

LUCIUS J. PHELPS.
